UNITED STATES PATENT OFFICE.

FRANK P. CALLAHAN, OF GRAF, IOWA.

CORN-PLANTER.

SPECIFICATION forming part of Letters Patent No. 778,109, dated December 20, 1904.

Application filed March 19, 1903. Serial No. 148,578.

To all whom it may concern:

Be it known that I, FRANK P. CALLAHAN, a citizen of the United States, residing at Graf, in the county of Dubuque and State of Iowa, have invented certain new and useful Improvements in Corn-Planters; and I do hereby declare the following to be a full, clear, and exact description of the invention, which will enable others skilled in the art to which it applies to make and use the same.

My invention relates to corn-planters, and has for its object to provide positive means for automatically dropping corn at regular intervals and in parallel rows and at the same time to furnish visible marks to direct the driver both as to the rows and the place where the corn has been dropped in the parallel rows.

A further object is to provide simple and effective means whereby all the irregularities of the soil, together with the initial dropping at the beginning of the rows, may be provided for under all circumstances and the planting at regular intervals in parallel rows easily and readily accomplished.

The details of construction whereby these and other objects are successfully accomplished are fully set out in the following specification when read in connection with the drawings accompanying the same.

Figure 1 is a perspective view of my improved corn-planter. Fig. 2 is a perspective view of the main frame and the swinging supplemental frame with the latter shown slightly raised above the main frame. Fig. 3 is a perspective of the axle and drive-wheel with means for throwing the wheel into and out of engagement with the axle. Fig. 4 is a section through the axle, thimble, and drive-wheel with parts cut away. Fig. 5 is a perspective view of a collar attached to the axle with the means for attaching the lever that operates the drive-wheel. Fig. 6 is a perspective view of the under side of a portion of the stationary supplemental frame, showing the locking mechanism, together with the gear-wheels for operating the seeding mechanism. Fig. 7 is a detail of one of the markers.

In the drawings similar figures of reference denote corresponding parts in each of the figures.

Making renewed reference to the drawings, 2 designates a main frame of substantially rectangular shape and composed of longitudinal side bars. A rear end bar 4 and the front ends 5 of the side bars are bent inwardly and connected with a tongue or draft 6. Near the rear and to the under face of the frame is journaled an axle 8, upon the ends of which are mounted carrying-wheels 10. These wheels 10 may be pivoted upon the axle by pawls and 60 ratchets, (not shown,) one set for each wheel, so that each wheel may turn independent of the other, and when the wheels are reversed the axle will cease to rotate. Upon the axle 8 is rigidly secured a thimble 12, (shown in Fig. 4,) and upon and around this thimble and the axle is set a drive-wheel 14, adapted to be rotated by friction upon the thimble 12. Journaled to the upper side bars of the frame is a shaft 15, upon which rotates a segmental 70 gear-wheel 16. The periphery of this wheel is provided with a cog or toothed section 17, and the hub 18 of this wheel is provided with cogs 19, into which the gears 13 of the drive-wheel 14 mesh and rotate the wheel 16. 75 These cogs are of sufficient length to permit the drive-wheel 14 to be moved along the axle when the wheel 14 is out of engagement with the thimble on the axle and still remain in mesh with the cogs 19.

The stationary supplemental frame 26, which is secured to the under side of the main frame 2, has bearings 27 at each end thereof. In these bearings is journaled a shaft 20, which extends to considerable distance upon both sides of the frame for the purpose presently to be described and is rotated by the gear-wheel 22, rigidly secured thereon. This wheel is rotated by its engagement with the wheel 16. The wheel 22 is provided with twice the number of cogs 18 that are upon the periphery of the segmental wheel 16, so that when the wheel 16 is rotated it will rotate the wheel 22 half-way around, and by means hereinafter described the cogs 17 on the wheel 16 will be 95 brought into engagement with the same cogs 18 on the wheel 22 at each revolution, and thereby control the dropping of the seed.

For the purpose of operating the seeding mechanism and also the marker, which indi-

cates where the corn has been dropped in each hill, the outer ends of the shaft 20 are provided with beveled gears 25. At right angles to and preferably beneath the main frame 2 5 is secured a stationary supplemental frame 26. This stationary supplemental frame consists of two parallel bars 28, curved at the center 29 over the wheel 22. The outer ends of the bars 28 are bent outwardly to form the bearings 30 for shafts 32. Upon each of the shafts 32 is set a beveled gear 33, adapted to mesh into the beveled gear 25. Outside of the bearings 30, at the forward end of the shaft 32, is attached a wheel 35, and near the circumference of the wheel, on the side, is a pin 36. To the pin 36 is pivoted a pitman 38, provided with a loop 39 at its outer end. In the seedbox may be a slide, (not shown,) which is provided with a bent arm 40, projecting out from 15 the seedbox 42 and adapted to engage in the loop 39 of the pitman 38. It will be seen that at each revolution of the wheel 35 the slide in the seedbox will be drawn out and forced in by the pitman 38, thereby dropping one hill 20 of corn at each revolution of the wheel 35. On the opposite end of the shaft 32 is set a wheel 45, to which is attached a marker-arm 46. This marker-arm is formed in two parts 47 and 48. (See Fig. 7.) The part 47 is 25 hinged to the part 48 a short distance below its upper end and is perforated near the top, through which a rod 49, attached to the part 48, projects. The rod 49 is provided with a stop 50 at its outer end, and between the stop 30 50 and the end of the part 47 is a coiled spring 51. The object of this construction is to provide means for the marker 46 to yield whenever it strikes any hard substance, and thus prevent it from being broken. The marker- 35 arm is adjustably attached to the wheel 45 by means of clip-bolts 44. This arm extends downward to a little below the base of the shoe presently to be described. As the wheel 45 is rotated the marker-arm 46 will turn with 40 the wheel and at each revolution strike the ground at right angles to the travel of the machine and mark the place where the corn has been dropped.

For the purpose of arresting the rotation 50 of the gears 25, and thus stay the seeding, the wheel 16 is perforated, and in the perforation is rigidly fastened a pin 52, which projects out at right angles a short distance on both sides of the wheel 16. To the under side of one of the 55 bars 28 of the stationary supplemental frame 26 there are suspended lever-arms 53, one on each side of the wheel 22. At one end of this lever 53 is an arm 54, which projects upward and at right angles and is adapted to engage the pin 52. The other end of the lever 53 is bent at 55 and is provided with a lug 56, adapted to engage in a slot 57 in the hub of each of the gear-wheels 25 and lock the wheels 25 in their 60 rotation. When the wheel 16 is rotated and 65 the first cog 17 next to the pin 52 commences

to engage with the cog 18 on the wheel 22, the pin 52 will come in contact with the arms 54, which will partially rotate the lever-arms 53 and will draw the lugs 56 out of engagement with the slots 57 on the hubs of the wheel 25 70 and permit them to be rotated and also permit the wheel 22 to be rotated by the wheel 16. It will be seen that the cogs 17 on the wheel 16 will engage one-half of the cogs on the wheel 22 at each revolution of said wheel 16 75 and will always commence to come into mesh at exact opposite sides of the wheel 22.

The seeding mechanism is constructed entirely independent of the main frame of the machine and has no connection with the draft, 80 but is forced along in front of the machine by the means hereinafter described. It consists in the shoes or furrow-openers 60, one upon each side, upon which are set the seedboxes 42. The seedboxes are rigidly connected together 85 by a bar 62. There are also braces 63 attached to the bar 62 and united to the forward end of the shoes; also, braces 64 run from the end of the shoes to the seedboxes 42. To the bar 62 is loosely attached two arms 68, which 90 extend backward and are rigidly secured to the shaft 15. Upon the shaft 15 is attached an operating-lever 70 for rotating the shaft 15 to raise the shoes and seeding mechanism.

Upon the shaft 15 and the stationary supplemental frame is set the usual sector-plate 95 65, and to the lever 70 is attached a spring-actuated dog or pawl 66, so that when the lever is thrown backward to raise the seeding mechanism the dog will engage with the 100 sector-plate and hold the seeding mechanism at the height desired.

From the above construction it will be seen that the bar 62, shaft 15, and connecting-arm 68 form a swinging supplemental frame 105 105 which is always above the main frame and which when raised by the lever 70 swings with the shaft 15 as fulcrum.

It will be seen as the arms 68 are loosely attached to the bar 62 that when the lever 70 110 is drawn backward the shaft 15 will be rotated and by the arms 68 the seeding mechanism will be raised practically perpendicular and without in any manner tilting the main frame of the machine and entirely independent 115 of the machine whenever it is necessary to pass an obstruction, turn a corner, or for whatever purpose. It will also be seen that the seeding mechanism is operated by itself and is independent in its movements of the main 120 frame and that the wheel 22 is never disturbed and will always remain in mesh or in proper position for mesh with the wheel 16. It will further be observed that the draft is not attached to the seeding mechanism, but the 125 whole seeding mechanism is forced forward from the shaft 15 by the engagement of the arms 68 with the bar 62.

For the purpose of marking the land, where- 130 by the driver will be able to guide his team

with one animal on each side of the marked line; there is attached to the rear end of the machine a marker 72 in the following manner: Between the side bars of the main frame, near the rear, is placed a cross-bar 74, and upon this bar and the rear of the cross-bar or frame 4 is journaled the marker-shaft 75, which is bent at right angles, and to the outer end is secured the marker 72. To the front end of the shaft 75 is secured a wheel 76, provided with two crescent-shaped slots 77. Against the cross-bar 74 is pivoted a lever 78, provided with holes 79, one near the lower end below the frame and the other about the same distance above the frame. In these holes is loosely attached rods 80, which engage with the slots 77, one in each slot. It will be seen that by operating lever 78 the marker 72 may be rotated to mark from either side of the planter and will mark at midway between the rows contiguous to the rows planted.

For the purpose of moving the drive-wheel 14 in and out of engagement with the thimble 12 upon the axle 8 and for otherwise controlling the action of the drive-wheel the hub 82 of the wheel is grooved at 83, and within this groove is loosely fastened a band 84, carrying lugs 85 upon its opposite sides. Around the axle 8 is also loosely fastened a collar 86 and provided with lugs 88 upon its opposite sides. The lugs 88 and 85 are connected together by bars 90, one on each side opposite. Between the collar 86 and the hub 82 there is rigidly fastened upon the axle a collar 92, provided with a groove 93, and within this groove is loosely secured a ring 94, carrying lug 95 upon one side. To this lug 95 is pivotally secured a lever 96, forked at its lower ends and extending downward upon opposite sides of the collar 92 and widened at 97, as shown in Fig. 3. For the purpose of rotating the wheel 14 without rotating the axle 8 there is attached to the hub 82 of the wheel 14 a ratchet 98, and upon the lever 96 is secured a pawl 99, adapted to engage with the teeth upon the ratchet 98, and when the lever 96 is drawn over toward the wheel, drawing it out of engagement with the thimble 12, the wheel 14 may be operated by the lever 96 operating the pawl 99 against the ratchet 98, and thus rotating the wheel 14.

The manner of operating my device is substantially as follows: The seed is placed in the seedboxes and the driver grasps the lever 96 and pushes it away from the wheel 14, which causes the part 97 to engage with the hub of the wheel and forces the wheel onto the thimble 12. The team is then started, and the rotation of the axle 8 rotates the wheel 14, which in turn rotates the wheel 16 by the engagement of the cogs 13 of the wheel 14 with the cogs 19 of the part 21 of the wheel 16. When the cogs 19 on the wheel 16 next to the pin 52 are about to engage with the cogs on the wheel 22, the pin 52 will come in contact with

the arms 54 on the lever-arms 53 and will partly rotate the levers sufficiently to draw the lugs 56 out of engagement with the slots 57 in the hubs of the wheels 25 and permit them to be rotated at the same time the wheel 16 rotates the wheel 22. The rotation of the wheel 16 will also rotate the wheel 22 one-half way around, and as the wheel 22 is fixed upon the shaft 20 the beveled gears 25 will be rotated, and at the same time the wheels 35 will also be rotated and the slides 40 drawn out to cause the seed to drop, and when the rotation of the wheel 35 is completed the slides will have been pushed back. At the same time that the seed is dropped the wheels 45 will be rotated and the marker 46 as the team advances will mark across at right angles to the place where the corn has been dropped in both rows. As the team advances the marker 72 will mark the line along the land parallel with the corn that has been planted and at the middle of the parallel rows to be planted on the return trip of the planter. When the ends of the rows are reached, the driver throws the lever 96 in an opposite direction, which releases the engagement of the wheel 14 with the thimble 12 and stops the rotation of the said wheel 14. He then grasps the lever 70 and draws it backward, which raises the shoes and the seeding mechanism entirely off of the ground without any tilting or movement of the main frame and independent of the main frame. When the driver has made the turn and if he finds that the shoes and the dropping mechanism are not in proper position to drop the corn, he advances the carrying-wheels 10 until the dropping mechanism is in proper position. If the driver then finds that when the shoes are in proper position for dropping the wheel 22 is not in proper engagement with wheel 16, so that immediately upon the starting of the team the dropping mechanism will commence operating, he grasps the lever 96 and rotates the wheel 14 by the engagement of the pawl 99 with the ratchet 98, which will rotate the wheel 14, and thus will rotate the wheel 16 until it will come in the proper place for engagement with wheel 22, then the driver by said lever 96 brings the wheel 14 into engagement with the thimble 12 and starts his team, and immediately upon the advance of the team the dropping mechanism will commence to operate. The team is then driven with one animal on each side of the line that the marker 72 has made when the two former parallel rows were planted. The driver also at the time when the team is started turns the lever 78 in the opposite direction, which throws the marker 72 on the opposite side of the machine in a position to mark the ground for a guide to the driver on his return planting. It will be seen that if the ground is uneven then the correction of the dropping mechanism may always be effected in the same manner as at the initial of the row. It will also

be seen that as each carrying-wheel may turn independent of the other and independent of the axle in one direction if one wheel advances over an obstruction it will make no difference 5 with the dropping mechanism, and if both wheels pass over some irregularities then the correction can be made as hereinbefore stated.

It will be observed that the driver has the entire machine under his control and the soil 10 is marked to indicate not only where the seed has been dropped, but also a line which indicates the direction he is to drive his team and at all times can correct any irregularities in the dropping, whereby the corn can be planted 15 practically in squares with almost as much accuracy as though the ground were absolutely level.

The various details of construction set out 20 and described herein may be varied within wide limits and parts of the features may be adopted without adopting it as a whole and still be within the spirit and scope of my invention.

Having now described my invention, what 25 I claim is—

1. In a corn-planter, the combination of a main frame having a draft connection secured at its front end and an axle journaled near its rear end, a swinging supplemental frame piv- 30 otally mounted on and above said main frame between the axle and the draft connection, a seeding mechanism secured to the front free end of said supplemental frame, and means for raising the seeding mechanism above and 35 independent of the main frame and of the draft connection.

2. In a corn-planter, the combination of a main frame having a draft connection secured at its front end and an axle journaled near its 40 rear end, a swinging supplemental frame having its rear end journaled in the main frame between the axle and the draft connection with its front free end disposed above the main frame, a seeding mechanism secured to 45 the front free end of said swinging supplemental frame, and a lever-arm extending from the rear journaled end of the swinging supplemental frame for raising the seeding mechanism above and independently of the main 50 frame and its draft connection.

3. In a corn-planter, the combination of a main frame having a draft connection secured at its front end and an axle journaled near its rear end, a swinging supplemental frame having 55 its rear end journaled in the main frame between the axle and the draft connection with its front free end disposed above the main frame and having its downward movement limited thereby, a seeding mechanism secured to the front free end of said supplemental frame, and means extending from the journaled end thereof for raising the seeding mechanism above and independently of the main frame and its draft connection.

4. In a corn-planter, the combination with

a main frame having a draft connection and an axle having carrying-wheels, of a seeding mechanism mounted above the main frame forward of the axle and having its downward movement limited by the main frame, means 70 for raising the seeding mechanism above the main frame independently thereof and of the draft connection, and means whereby the seeding mechanism is impelled by the frame in front of the carrying-wheels and independ- 75 ently of the draft.

5. In a corn-planter, a main frame, an axle, carrying-wheels, a driving-wheel, a seeding mechanism mounted above the frame forward of the axle, connections between the drive-wheel and the seeding mechanism for operating the latter, a shaft pivoted in the frame in advance of the axle and connected with the seeding mechanism, means for attaching the draft to the main frame without connection 80 with the seeding mechanism, and a lever on the shaft for rocking the latter to raise the seeding mechanism above and independent of the main frame.

6. In a corn-planter, the combination with 90 a main frame having a draft connection and an axle having carrying-wheels, of a seeding mechanism mounted above the main frame forward of the axle and capable of being raised above the main frame independently thereof and of the draft connection.

7. In a corn-planter, the combination with a main frame having an axle and carrying-wheels, and a draft connection at its forward end, of a seeding mechanism mounted above 100 the main frame and connected therewith in the rear of the draft and in front of the axle, means for raising the seeding mechanism above the main frame independently thereof and of the draft connection, a drive-wheel 105 upon the axle, a segmental gear-wheel driven by the drive-wheel, mechanism in engagement with the segmental gear-wheel and the seeding mechanism for operating the latter, means engaging the seeding mechanism to lock it 110 against operation, and means on the segmental gear-wheel co-operating with the said locking means to disengage it from the said operating mechanism.

8. In a corn-planter, a main frame, a rotat- 115 ing axle, carrying-wheels, a seeding mechanism supported on top of the main frame, a shaft attached to the main frame, arms rigidly attached to the shaft and engaging the seeding mechanism, and a lever for operating the 120 shaft to raise the seeding mechanism above and independent of the main frame.

9. In a corn-planter, the combination with a main frame having a draft connection at its front end, of a swinging supplemental frame 125 carrying a seeding mechanism, connected with the main frame in the rear of the draft and capable of being swung upwardly independ- ently of the main frame and the draft, a rock- shaft journaled in the main frame in the rear 130

of the seeding mechanism and having a rigid connection with the latter, and means including the rock-shaft for raising the frame carrying the seeding mechanism.

5. 10. In a corn-planter, the combination with a main frame having a draft connection at its front end, of a swinging supplemental frame carrying a seeding mechanism and mounted above the main frame in the rear of the draft, 70
10 a driving mechanism for the seeding mechanism, a rock-shaft journaled in the frame, a connection between the rock-shaft and the seeding mechanism, said shaft constituting a journal for one member of the said operating 75
15 mechanism and also including means for raising the frame carrying the seeding mechanism.

11. In a corn-planter, a main frame, means for attaching the draft to said frame, an axle, carrying-wheels, a drive-wheel upon the axle, 20
20 a shaft in front of the axle, a segmental gear-wheel journaled on the shaft and driven by the drive-wheel, a swinging frame carrying a seeding mechanism connected with the main frame in the rear of the draft attachment and 25
25 adapted to be advanced by its connection with the frame, means connected with the segmental gear-wheel for operating the seeding mechanism, and means including the shaft for raising the frame carrying the seeding mechanism.

30. 12. In a corn-planter, a main frame, means for attaching the draft to the main frame, an axle, carrying-wheels, a driving-gear upon the axle, a segmental gear-wheel driven by the driving-gear, a seeding mechanism pivoted to the main frame and capable of being raised thereabove and driven by its connection to said frame, a lever for raising the seeding mechanism without movement of the main frame, and means engaging the segmental 35
40 gear-wheels to operate the seeding mechanism.

13. In a corn-planter, a main frame, a draft attachment secured to said frame, a rotating axle, carrying-wheels, a driving-gear on the axle, a segmental gear-wheel driven by the driving-gear, a seeding mechanism having a 45
45 swinging movement relative to the main frame and supported thereby, a gear-wheel driven by the segmental gear-wheel, connections between said gear-wheel and the seeding mechanism to operate the latter to drop the grain at regular intervals, and means for raising the seeding mechanism without raising its operating mechanism, the drive-wheel or the main frame.

55. 14. In a corn-planter, a main frame, a draft attachment secured to the frame, a rotating axle, carrying-wheels, a drive-wheel, a segmental gear-wheel driven by the drive-wheel, a seeding mechanism pivoted to the frame and 50
60 adapted to be raised without movement of the main frame, a shaft attached to said frame, a gear-wheel upon the shaft adapted to be driven by the segmental gear-wheel, a gear-wheel upon each end of the said shaft, and connections between the last-mentioned gear-wheels

and the seeding mechanism for operating the latter.

15. In a corn-planter, a main frame, an axle having a drive-wheel mounted thereon and adapted to be frictionally driven thereby, a seeding mechanism, adjunctive mechanism between the seeding mechanism and the drive-wheel for operating the said seeding mechanism, means for throwing the drive-wheel out of frictional engagement with the axle, means 75
75 co-operating with the drive-wheel for advancing the seeding mechanism when the drive-wheel is thrown out of engagement with the axle, and means for raising the seeding mechanism independent of its operating mechanism 80
80 and of the main frame.

16. In a corn-planter, a main frame, an axle having a drive-wheel mounted thereon and adapted to be frictionally driven thereby, a segmental gear-wheel driven by the drive-wheel, a shaft attached to the main frame having a gear-wheel thereon adapted to be driven by the segmental gear-wheel, a seeding mechanism, connections between the said shaft and the seeding mechanism for operating the latter, means for raising the seeding mechanism independent of its operating mechanism and 85
85 of the main frame, means on the axle for throwing the drive-wheel out of frictional engagement therewith and for operating said drive-wheel to advance the seeding mechanism when the drive-wheel is out of operative relation with the axle.

17. In a corn-planter, a main frame, an axle, carrying-wheels, a drive-wheel upon the axle, 90
90 a shaft journaled in the main frame, a segmental gear-wheel journaled on said shaft and driven by the drive-wheel, a seeding mechanism, means connected with and driven by the segmental gear-wheel for operating the seeding mechanism, means carried by said operating mechanism for the seeding mechanism for locking the latter against operation, means carried by the segmental gear-wheel for releasing said locking means, and means for 95
100 raising the seeding mechanism with the shaft as an axis without raising the operating mechanism or the main frame.

18. In a corn-planter, a main frame, an axle, carrying-wheels, a drive-wheel, a seeding mechanism, a shaft journaled to said frame, a gear-wheel on each end of the shaft, a supplemental stationary frame attached transversely to the main frame, and a locking mechanism attached to the supplemental frame and engaging the gear-wheels on the ends of the shaft to prevent dropping of the corn only when the drive-wheel is in operative engagement with the axle.

19. In a corn-planter, the combination with a main frame having an axle and carrying-wheels and a draft connection at its forward end, of a seeding mechanism mounted above the frame and connected therewith in the rear of the draft, a drive-wheel upon the axle, a 125
125

65

- segmental gear driven by the drive-wheel, mechanism in engagement with the segmental gear-wheel and the seeding mechanism for operating the latter, means engaging the seeding mechanism to lock it against operation, and means on the segmental gear-wheel co-operating with said locking means to disengage it from the said operating mechanism, substantially as set forth.
20. In a corn-planter, a main frame, a draft attachment secured to said frame, a rotating axle, carrying-wheels, a drive-wheel, a segmental gear-wheel driven by the drive-wheel, a seeding mechanism pivoted to the main frame and adapted to be raised without movement of the frame, a shaft attached to the frame, a gear-wheel upon the said shaft adapted to be driven by the segmental gear-wheel, a gear-wheel upon each end of the said shaft, and a lock adapted to engage the gear-wheels upon the ends of the shaft, and segmental wheels to prevent the dropping of the seed when the gear-wheel upon the shaft is out of engagement with the segmental gear-wheel.
21. In a corn-planter, a main frame, carrying-wheels, a rotating axle, a drive-wheel on the axle, a segmental gear-wheel rotated by the drive-wheel, a shaft journaled to the main frame, a gear-wheel upon said shaft, a supplemental stationary frame, a marker-shaft, and

means connected with the first-mentioned shaft for operating the marker-shaft to mark the soil at the place of the dropping of the seed.

22. In a corn-planter, a main frame, an axle, carrying-wheels, a stationary supplemental frame secured transversely to the main frame, a shaft pivoted to each end of the said stationary supplemental frame, a yielding marker attached to the shaft, and means for rotating the shaft to operate the marker.

23. In a corn-planter, a main frame, carrying-wheels, a rotating axle, a driving gear-wheel upon the axle, means for engaging and disengaging the driving-wheel with the axle, a segmental gear-wheel adapted to be driven by the drive-wheel, a shaft journaled to the frame, a gear-wheel upon the shaft adapted to be rotated by the segmental gear-wheel, a gear upon each end of the shaft, a dropping mechanism, and means connected with the said gear-wheels for operating the dropping mechanism.

In testimony whereof I have signed my name to this specification in the presence of two subscribing witnesses.

FRANK P. CALLAHAN.
